UNITED STATES PATENT OFFICE.

ADOLPH SCHOENINGER, OF CHICAGO, ILLINOIS.

CRUTCH.

SPECIFICATION forming part of Letters Patent No. 288,368, dated November 13, 1883.

Application filed January 5, 1883. (No model.)

To all whom it may concern:

Be it known that I, ADOLPH SCHOENINGER, of Chicago, in the county of Cook and State of Illinois, have invented certain new and useful 5 Improvements in Crutches; and I do hereby declare that the following is a full, clear, and exact description thereof, reference being had to the accompanying drawings, and to the letters of reference marked thereon, which form 10 a part of this specification.

This invention relates to certain improvements in the construction of crutches, as will be hereinafter described and claimed.

In the drawings, Figure 1 represents an elevation of a crutch constructed according to my 15 improvements. Fig. 2 is a horizontal section on the line *x x* of Fig. 1. Fig. 3 shows in longitudinal section, and to an enlarged scale, the lower extremity of the crutch.

20 According to my invention, in constructing the staff or standard *a*, I take a cylindrical piece, of some suitable wood or material usually employed in the construction of crutches, and split the same centrally from the top down 25 toward the lower extremity. I then, by the aid of steam, bend or curve the split members into the customary shape, with outwardly-curved upper ends, *b*, and bowed center *c*. Then to clamp that portion of the staff where 30 the split terminates, and confine the two members and prevent their further splitting apart, I encircle the lower split portions with a ring, *d*, which I attach to the staff by wood-screws *e*, as shown.

35 *f* represents the handle or hand-rest, by which the user grasps the crutch while in use. This handle, according to my invention, is centrally bored or recessed, and has an iron rod, *g*, passed therethrough, as shown in Fig. 2, the 40 two ends of which rod extend beyond the ends of the handle *f*, and are passed through holes in the split members of the staff, to which they are bolted, as shown. By this means it will be observed that the handle and rod form a 45 reliable brace, which holds the split portions of the staff or standard apart and rigidly in proper position.

h represents the arm-rest, which may be shaped out of a solid piece of wood, or bent into 50 the required form, or formed out of any other

suitable material. The upwardly-curved ends *i* of this arm-rest are rigidly attached to the outwardly-curved upper ends, *b*, of the staff or standard *a* by bolts or other suitable connections, *l*, whereby a firm and rigid connection of the arm-rest and staff is secured, and the split members of the staff are still further braced and held rigidly in proper position without the possibility of their spreading outward or buckling inward.

m represents a ferrule, which is provided at its upper end with a socket, *n*, to receive the lower end or extremity of the staff *a*, and at its lower end with a screw-threaded socket, *o*, within which a rubber or other elastic plug, 65 *p*, is screwed. Between the upper and lower ends of this ferrule I form, in said ferrule, interiorly, a shoulder, *q*, which serves as a seat for a washer, *r*, which is secured within said ferrule by a wood-screw, *s*, said screw passing 70 within the lower extremity of the staff or standard *a*, as shown, and serving to connect the staff and ferrule together. This washer *r* also serves as a bearing or rest against which the inner end of the rubber or elastic plug *p* 75 will rest and have bearing when screwed within the lower end of the ferrule.

By my improvements I produce a light, cheap, and strong crutch, the several parts of which may be readily placed in position or 80 taken apart when desired. The whole of the parts are rigidly held or braced together and prevented from spreading or buckling out of position.

The staff *a* can be made as well of two separate bars of bent wood that by and between ring *d* and ferrule *m* are secured against each other.

By securing the arm-rest and the handle to the staff by bolts and nuts they can be readily removed when required, and can also be tightened or loosened thereon, as occasion may require, during the use of the crutch.

Having thus described my invention, what I claim therein is—

1. A crutch having its staff or standard *a* formed of a cylindrical piece, split and steam bent or curved, substantially as described, and having outwardly-curved upper ends, *b*, the upwardly-curved and standard-bracing arm- 100

rest *h*, secured at each end to the upper ends of the standard by bolts and nuts, whereby said braces may be adjusted to the staff, substantially as and for the purpose set forth.

5 2. The combination of ferrule *m*, having socket *o* and shoulder *q*, and the washer *r*, and wood-screw *s*, substantially as and for the purpose set forth.

3. The combination of the ferrule *m*, having 10 socket *n*, screw-threaded socket *o*, and shoul-

der *q*, the washer *r*, and wood-screw *s*, and elastic plug *p*, substantially as and for the purpose set forth.

In testimony that I claim the foregoing as my invention I affix my signature in presence 15 of two witnesses.

ADOLPH SCHOENINGER.
